UNITED STATES PATENT OFFICE.

AUSBIN D. KANDLE, OF PENCOYD, PENNSYLVANIA, ASSIGNOR TO KANDLE SANITARY HEAD REST MANUFACTURING COMPANY, A CORPORATION OF NEW JERSEY.

HEAD-REST.

No. 849,135.

Specification of Letters Patent.

Patented April 2, 1907.

Application filed March 16, 1905. Serial No. 250,463.

To all whom it may concern:

Be it known that I, AUSBIN D. KANDLE, a citizen of the United States, residing at Pen-coyd, in the county of Montgomery and State of Pennsylvania, have made certain new and useful Improvements in Head-Rests, of which the following is a specification.

My invention is an improvement in head-rests for barbers' chairs, and consists in certain novel constructions and combinations of parts, as will be hereinafter described and claimed.

In the drawings, Figure 1 is a perspective view of a head-rest provided with my improvements. Fig. 2 is a cross-sectional view of the paper cutter and guide. Fig. 3 is a detail view of the base of the paper-guide, and Fig. 4 is a detail view of the rocker.

The head-rest A is suitably supported, and below it is secured a cylinder B, containing a paper-roll. The paper is drawn from this cylinder up over the head-rest A and thence through the combined paper cutter and guide C. This device includes a base-plate D, provided at its ends with the upturned lugs E, formed by cutting out the base-plate and turning up the slitted or cut-out portions to form the lugs, as shown. The base-plate is also provided with depending lugs d, secured to the back of the head-rest, and the rear edge of the base-plate is cut out at d to permit the operator to readily grasp the end of the strip of paper to draw the same through the guiding device.

The lugs or ears E form the bearings for the rocker, which will be described more fully hereinafter. The front end portion of the base-plate D is extended considerably forward of said lugs to form a transversely-extending strip or bed D', with which the adjacent edge of the binding-plate of the rocker is adapted to engage, so as to press the paper firmly against said base-plate and hold the same against improper shifting. The bed is somewhat returned on itself, forming a corrugation or channel which constitutes a bead, serving to stiffen or reinforce the portion of the base-plate with which said binding-plate of the rocker engages.

The rocker F comprises a rod or shaft F', journaled in the lugs E, and the binding-plate F², cutter-plate F³, and handle F⁴. The binder-plate F² and the cutter-plate F³ are at an angle to each other and fit over the shaft

F', and a spring G is arranged to actuate the rocker in such manner as to press the binding-plate normally down against the base-plate to hold the paper securely thereto. This spring G is shown as a coil-spring wound around the shaft F' and engaging at one end with the base-plate D and at its other end against the rocker to press the rocker into contact with the base-plate.

The cutter-plate F³ has its free edge sharpened, and preferably serrated, so it will readily cut the paper when drawn across such edge. It will be noticed that the rocker is normally pressed by the spring G to position to hold the free edge of the paper when the latter is drawn tightly across the head-rest, the handle F⁴ being so disposed that it can be conveniently operated to tilt the rocker so the binding-plate thereof may be raised clear of the base-plate and the cutting edge be adjusted down against the base-plate to facilitate cutting off the portion of paper that has been used, when by quickly releasing the rocker it will spring back, causing its binding-plate to press the paper tightly against the base-plate with its free end projecting over the notched-out portion d of the base-plate so it can be readily grasped by the operator.

The construction is simple and can be easily applied to a head-rest and enables the barber to quickly draw the paper that has been used from the head-rest, bringing a fresh section over the head-rest, and to quickly cut off the paper that has been used.

Having thus described my invention, what I claim as new, and desire to secure by Letters Patent, is—

1. The combination with a head-rest of a guiding device for paper comprising a base-plate having its front edge returned forming a bead or strip along its upper side and its rear edge notched or cut away to permit the free edge of a sheet of paper to be grasped and having lugs for connection with a head-rest and upwardly-projecting bearing-lugs, a rocker comprising a handle by which it may be rocked, a shaft journaled in the bearing-lugs of the base-plate, a binding-plate and a cutter-plate at an angle to each other and fitting over the shaft, and a spring coiled on the shaft and bearing at one end against the base-plate and at its other end against the rocker to actuate the latter.

2. The combination in a paper-holding device of a base-plate having a forwardly-extending bed, a rocker pivoted in connection with the base-plate and comprising a cutter-plate and a binding-plate arranged at an angle to the cutter-plate and adapted to bear at its free edge normally against the base-plate adjacent to the bed thereon and a spring actuating said rocker.
- 10 3. In a paper guiding and holding device, a base-plate, lugs on said base-plate, an angular rocker pivotally supported on said lugs

with both edges at all times within the confines of the width of said base-plate with one edge adapted to contact with said base-plate to bind the paper thereagainst and its other edge constituting a cutter adapted to press the paper against said plate, and a spring confined between the angular sides of said rocker, upon the pivot thereof.

AUSBIN D. KANDLE.
